UNITED STATES PATENT OFFICE.

CYRUS A. McCAIN, OF CHICAGO, ILLINOIS.

CUSHIONING MECHANISM FOR RECIPROCATING BEDS.

No. 845,429.

Specification of Letters Patent.

Patented Feb. 26, 1907.

Application filed March 5, 1906. Serial No. 304,287.

To all whom it may concern:

Be it known that I, CYRUS A. McCAIN, a citizen of the United States, residing at Chicago, in the county of Cook and State of Illinois, have invented a new and useful Improvement in Cushioning Mechanism for Reciprocating Beds, of which the following is a specification.

My invention relates to improvements in pneumatic cushioning means for reciprocating beds, and more especially for the beds of printing-presses.

My object is to provide cushioning means of improved construction which will operate automatically to regulate the cushioning resistance in accordance with the speed of reciprocation of the bed.

In carrying out my invention I provide pistons to enter cylinders in the movement of the bed toward the end of its traverse in each direction, either the pistons or the cylinders, and preferably the former, being fastened to the bed to travel therewith. In either the pistons or the cylinders, preferably the former, I provide vent-openings of suitable size governed by normally unseated valves of special construction and so arranged that they will remain open to prevent any cushioning action when the bed is reciprocated, as by hand, at slow speed, and will close in the more rapid reciprocation of the bed in a manner to initiate the cushioning resistance sooner or later, according to the speed of reciprocation of the bed, thereby to properly regulate the degree of cushioning. I have found in practice that to provide valves which will operate with necessary certainty to produce the desired cushioning effect they must be of disk or ring form held normally open by springs of suitable tension and each present a large area, as compared with the area of the vent-opening which it governs, to the cylinder air contents, in order that it may be suitably sensitive for the performance of its function. In order that the operation of the valves may be under proper control, it is necessary that the pistons shall properly fit the cylinders, and for this purpose I provide pistons of novel construction each with an adjustable packing-ring and improved adjusting means for the packing-ring.

Referring to the drawings, Figure 1 is a broken sectional view showing a cylinder and a piston of my improved construction provided with the cushioning-valve; Fig. 2, an

enlarged broken sectional view of the piston; Fig. 3, a face view of the piston intact; Fig. 4, a similar view of the piston with the disk or ring valve removed and showing the adjustable expanding means for the piston-packing; Fig. 5, a section, on a reduced scale taken on line 5 in Fig. 2 and showing the rear side of the piston; Fig. 6, a view in elevation of the disk or ring valve, showing its seating face, and Fig. 7 an enlarged view of one of three segmental expanding members for the piston-packing.

The cylinder 8 has a closed end, or head 9, and is of a form commonly employed in printing-presses. The piston-stem 10 has a threaded end portion 11, on which the piston 12 is screwed and locked against rotation by a nut 13. The body of the piston consists of a metal disk having a central externally-threaded hub or boss 14. Equidistant around the hub are three or three pairs of openings 15 through the piston, forming an annular series of vent-ports, and between the said openings the piston is formed with deep sockets 16. The said sockets have annular shoulders 17, beyond which they are formed with reduced threaded receptacles 18 to hold adjusting-screws 19. Surrounding the hub 14 is a disk or ring 20, having perforations 21 to receive the screws 19, on which the ring is thus slidily mounted and which form guides for the ring. The ring is provided with seating projections 22, of rubber, leather, or the like, adapted to seat over and close the vent-openings 15. In the sockets 16 are coil-springs 23, confined between the shoulders 17 and the disk or ring 20 and operating normally to press the latter against the heads of the guide and adjusting screws 19.

Around the piston is a cupped, preferably leather, packing 24, forming the peripheral face of the piston and extending against the rear side thereof around the openings 15 and socket projections described. Fitting against the packing at the rear side of the piston is a clamping-ring 25, fastened thereto by means of screws 26, to clamp the packing in place.

On the working face of the piston is packing-expanding means comprising a cupped disk formed of relatively adjustable segmental members 27, having the peripheral flanges 28. The inner circular edges 29 of the segments are beveled, as shown, and the segments have cut-away portions 30 to clear the valve-seating projections 22 and elon-

gated openings 31 and 32 in the positions indicated. The openings 32 form guides, which receive pins or studs 33, projecting from the adjacent face of the piston. The 5 openings 31 also form guides and receive fastening-screws 34, which enter threaded sockets in the adjacent face of the piston and tighten the segments 27 in their adjusted position. The segments are provided with 10 outer slits 35 in their flanges 28 and slits 35^a, extending from the cut-away portions 30 to give to the segments a springy character whereby they may expand and contract laterally. On the threaded boss 14 is a nut 36, 15 formed into an annular wedge 37 to engage the beveled inner ends of the segments. Turning of the nut 36 in one direction causes its wedge-shaped end to bear against the ends 29 and force the segments radially outward. As the latter slide upon the guides 20 33 34 they are caused to stretch or expand slightly and fit perfectly against the inner circumference of the packing 24. The guide-screws 34 may be turned to fasten the segments securely in adjusted position. Thus 25 it will be seen that by turning the nut 36 the packing 24 may be expanded to fit with desired closeness the cylinder 8, and in the event of wear of the packing it may be expanded from time to time to maintain its fit 30 in the cylinder. Extending through the nut 36 is a set-screw 38 for fastening it against turning on the boss 14.

In practice the packing is expanded to fit 35 with desired closeness the cylinder 8 and the screws 19 are adjusted to normally position the disk or ring valve 20 under tension of the springs 23 at the desired distance from the seating faces of the ports or vent-openings 40 15. The annular opening around the disk or ring 20 should be of just the proper area to permit air to pass through to the rear side of the disk or ring to the ports 15 in a manner to prevent air-pressure from closing the disk 45 or ring valve except when pressure accumulates in the cylinder faster than it can vent around the disk or ring to the ports. The parts are adjusted with relation to the tension of the springs 23 by means of the screws 50 19, so that when the piston enters the cylinder at comparatively slow speed it will not be able to compress the air therein to an extent which would effect closing movement of the valve device. In a somewhat faster 55 movement of the piston into the cylinder the air will not be able to escape quite fast enough to compensate for the displacement of the piston, and when the latter approaches nearly to the end 9 the pressure will have accumulated sufficiently to close the valve device, confining the remaining pressure for a 60 comparatively slight cushioning purpose. The faster the piston moves on entering the cylinder the sooner, therefore, will the valve device be closed and the greater the cushion-

ng effect of the confined air. When running at the highest speed, most of the air contained in the cylinder when the piston starts to enter may be trapped to cushion the reciprocating bed. Thus the degree of cushioning will be governed entirely by the speed of reciprocation.

As before stated, I have found in practice that to effect the desired results with sufficient certainty the valve device should 75 be constructed to operate substantially as shown and described, and no other valve construction of which I am aware will fulfil my object. Besides operating with great 80 certainty in producing the desired cushioning effect it is practically noiseless in operation and self-contained. It dispenses with pipes, cocks, and other attachments usually employed in other cushioning means intended for the same purpose.

As I prefer to employ my improvements the cylinders are stationary and the pistons reciprocate with the bed. The valve devices are thus more or less affected by momentum in their movement with the pistons. This 90 momentum tends to quicken the closing and opening movements of the valves at the beginning and end of the cushioning action, which I have found to be an advantage.

A ring and a disk are the equivalents of 95 each other as applied to the part 20, which is shown to be of annular form merely to permit the employment of the packing-adjusting nut 36 in the relative position shown.

The slits 35 operate to render the flange portion 28 of the segments yielding, so that in the event that the packing is expanded unduly it may yield in passing into the cylinder and prevent its sticking or sliding in the cylinder with too great friction. The shape of 100 the packing 24 and the construction of the parts 27 causes the packing while air is being compressed in the cylinder to be pressed by the air against the wall of the cylinder and produce at all times a properly-tight fit. At 105 the same time it leaves the annular edge of the sliding valve device free and permits air to rush around all parts thereof equally and maintain the valve properly balanced. Another advantage of my improved construction lies in the fact that when the pistons start on their return strokes in the direction 110 away from the cylinder-heads the springs open the valve devices before the pistons can commence to draw a vacuum. Thus even 115 when the bed is reciprocating at highest speed there will at no time be any suction action in the cylinders while valves are being opened, which would tend to retard free movement of the bed and attendant parts.

What I claim as new, and desire to secure by Letters Patent, is—

1. In a cushioning device for reciprocating beds, the combination with cushioning members, one stationary and the other movable

with the bed, and consisting of a piston and a cylinder, of cushion-regulating means on one member comprising an annular series of vent-ports, a sliding, normally open ring or disk valve governing said vent-ports, guiding means for the valve, and spring controlling means for the valve acting counter to pressure in the cylinder.

2. In a cushioning device for reciprocating beds, the combination with cushioning members, one stationary and the other movable with the bed, and consisting of a piston and a cylinder, of cushion-regulating means on one member comprising an annular series of vent-ports, a sliding normally open ring or disk valve governing said vent-ports, guiding means for the valve, unseating springs for the valve acting counter to pressure in the cylinder, and adjusting means for the springs.

3. In a cushioning device for reciprocating beds, the combination with cushioning members, one stationary and the other movable with the bed, and consisting of a piston and a cylinder, an annular series of vent-ports in the cylinder, a sliding ring or disk valve carried by the piston and governing said vent-port therein, guides on the piston on which the valve slides, and springs interposed between the piston and valve acting counter to pressure in the cylinder.

4. The combination with a piston, of a circumferential packing carried thereby, and means for expanding the packing, comprising a cup-shaped disk on the piston formed of radially-adjustable segmental members, inherently expandible and contractible to de-

scribe, at packing-engaging surfaces, varying arcs at different positions of adjustment, and means for forcing the segments outwardly against the packing whereby the periphery of said cup-shaped disk will always be approximately circular.

5. The combination with a piston, of a circumferential packing carried thereby, and means for expanding the packing, comprising a cup-shaped disk on the piston formed of radially-adjustable segmental members, inherently expandible and contractible to describe, at packing-engaging surfaces, varying arcs at different positions of adjustment, means for forcing the segments outwardly against the packing, and means for expanding the segments as they are forced in the outward direction whereby the periphery of said cup-shaped disk will always be approximately circular.

6. The combination with a piston, of a circumferential packing carried thereby and means for expanding the packing, comprising a cup-shaped disk on the piston formed of radially-adjustable segmental members, slotted to render them inherently expandible and contractible to describe, at packing-engaging surfaces, varying arcs at different positions of adjustment, and means for forcing the segments outwardly against the packing whereby the periphery of said cup-shaped disk will always be approximately circular.
